THE NORRIS PETERS CO., WASHINGTON, D. C.

UNITED STATES PATENT OFFICE.

JOHN WALTER FINCH, OF ELIZABETH, MISSISSIPPI.

HAND-CAR.

No. 879,756.

Specification of Letters Patent.

Patented Feb. 18, 1908.

Application filed July 16, 1907. Serial No. 383,966.

To all whom it may concern:

Be it known that I, JOHN W. FINCH, a citizen of the United States, residing at Elizabeth, in the county of Washington and State 5 of Mississippi, have invented a new and useful Improvement in Hand-Cars, of which the following is a specification.

This invention relates to hand cars, and has for its object to provide improved means 10 for driving the same, particularly with respect to the driving connections between the rocking or working lever and a planetary gearing from which motion is transmitted to the wheels.

15 The invention is illustrated in the accompanying drawings, in which

Figures 1, 2 and 3 are side elevations with the parts in different positions. Fig. 4 is an end elevation.

20 The hand-car frame of ordinary construction is indicated at 5, mounted on wheels 6 and having on the platform a pedestal 7 of suitable construction. The working or rocking lever 8, having handles 9 at opposite ends 25 is conveniently made of piping properly braced, and is fulcrumed by means of a rock shaft 10 upon the pedestal, and this shaft has keyed or otherwise fastened thereon a segment 11 which accordingly vibrates with the 30 rocking lever. It may be preferred to secure the segment 11 by a set screw 11^a so said segment can be moved to suit the one on the pitman to any angle to correspond. Said segment is in mesh with a companion segment 35 12 fast upon a stub shaft 13 which is connected to the shaft 10 by a pair of swinging links 14 free to turn upon both of said shafts.

The shaft 13 is connected by pitman 15 to 40 a stub shaft 16 which has a squared portion carrying the planet spur gear 17 which revolves around and rotates the sun gear 18 whose shaft 19 is mounted in bearings 20 on the frame of the car. The pitman 15 is rigidly fixed to both shafts 13 and 16. This is 45 conveniently done by squaring said shafts and the holes in the ends of the pitman through which they extend. The shafts 16 and 19 are connected by a pair of swinging 50 links 21. Said shaft 19 has thereon a relatively large sprocket wheel 22 belted by chain 23 to a small sprocket 24 on one of the axles of the car.

The rocking lever 8 has the ordinary rocking motion, and in consequence of the use of 55 the segment gears 11 and 12 the lateral

swing or motion of the pitman incident to the revolution of the planet gear around the sun is effected under pressure. In other words the pitman and the segment 12, being 60 rigid with each other, form a bent lever to throw the parts over the dead centers. Thus, Fig. 1 shows the lever in level or middle position; Fig. 2 swung one way and Fig. 3 the other. Starting from the position shown in 65 Fig. 2, when the lever is rocked toward the level position, the gear 17 starts to turn or revolve around the sun gear 18, and after passing the quarter or middle position shown in Fig. 1 the segment 11 acts on the segment 12 and 70 pitman 15, the whole forming a geared bent lever tending to throw or turn the planet gear over the top center, and the same effect results during the last quarter of the double stroke, or while approaching and passing the 75 lower center. The arrangement shown utilizes the whole force or leverage of the rocking lever during the entire stroke. Obviously, if the pitman were directly connected to the rocking lever, much of the applied 80 force would be ineffective when approaching or leaving centers.

The present device gives great or full power for force applied and therefore requires less power to drive the car. There is 85 also less strain on the links 21, since the leverage applied to the pitman tends to hold the planet and sun gears in mesh.

I claim

1. In a driving mechanism, the combination 90 of a rocking lever having a gear thereon, a sun and planet gearing, and a combined bent lever and pitman supported between the planet gear and the lever and having a gear in mesh with the gear on the lever. 95

2. In a driving mechanism, the combination 100 of a rocking lever having a segment gear fastened thereto, a sun and planet gearing, a combined bent lever and pitman one end of which is connected to the planet gear and the other end of which is provided with a segment gear meshing with said segment gear, and a swinging link connecting the pivots of the rocking and bent levers.

3. In a driving mechanism for a hand car, 105 the combination with a rocking lever pivoted on the pedestal of the car, a sun and planet gearing mounted on the frame of the car and geared to an axle thereof, a pitman one end of which is connected to the planet gear, 110 swinging links connecting the other end thereof to the pivot of the rocking lever, and

a segment gear rigid with the pitman and forming a bent lever therewith and another segment gear rigid with the rocking lever and meshing with the segment gear of the pitman.

4. The combination of a sun and planet gearing, a bent lever one arm of which forms a pitman and is connected at its end to the planet gear and the other arm of which has a

segment gear, a rocking lever, a pair of links connecting the pivots of said levers, and a segment gear fast on the pivot of the rocking lever and in mesh with the said segment gear.

JOHN WALTER FINCH.
